UNITED STATES PATENT OFFICE.

FRANK A. PHILLIPPI, OF READING, PENNSYLVANIA, ASSIGNOR OF THREE-FOURTHS TO CHARLES J. CLARK AND SAMUEL LUTZ, OF SAME PLACE.

VOLTAIC BELT.

SPECIFICATION forming part of Letters Patent No. 416,803, dated December 10, 1889.

Application filed May 7, 1889. Serial No. 309,914. (No model.)

To all whom it may concern:

Be it known that I, FRANK A. PHILLIPPI, a citizen of the United States, residing at Reading, in the county of Berks, State of Pennsylvania, have invented certain new and useful Improvements in Voltaic Belts, of which the following is a specification, reference being had therein to the accompanying drawings.

- 10 My invention has for its object the provision of a voltaic belt for therapeutic purposes, and it is my intention that my belt shall be adjustable, so as to provide a circuit which may be divided into two parts where more local treatment is desired. To this end I have constructed my belt in the manner described in the following specification, and with the novel features pointed out in the claims at the end of the same.
- 15 20 In the drawings, Figure 1 is a front view of my belt, showing the water-proof flap raised. Fig. 2 is a horizontal section on the line *y y* of Fig. 1, the flap being buttoned down. Fig. 3 is a rear view of my cell-chain detached 25 from the belt, and Fig. 4 is a vertical section on the line *x x* of Fig. 1.

Like letters of reference refer to like parts in all the figures of the drawings.

The belt proper may be made of any textile material; but I prefer to use woolen cloth or flannel A, faced with water-proof material, as rubber A'. The woolen cloth is brought next to the body of the wearer, the rubber being turned outward.

35 As preferably constructed my belt is made in three sections—a battery-section B and two end sections B'—the whole being connected by preferably elastic straps C, and the belt is fastened in place by means of the 40 buckles C'. A duplicate fold of water-proof material B² is fastened along the top of the battery-section B, and is adapted to fold over the front of the same and be fastened by means of the buttons B³. Fastened on the 45 front or water-proof face of the battery-section are three vertical strips D D' D². These strips are fastened to the belt by means of buttons E E' E² at the middle and at the opposite ends of said strips, respectively, and 50 forming electrodes with the same. The strips

may be made of any convenient metal, German silver being preferred. Spring-buttons F', F², and F are attached to these strips between their ends for fastening the cell-chain or battery proper to the belt. Buttons of this kind are preferably employed; but it is evident that any form of fastening may be employed whereby the cell-chain may be secured to said strips.

The cell-chain which provides the electric current in my device is composed of any desired number of cells, which may or may not be connected with the central strip D. As preferably constructed, however, my chain is divided into two sections, as shown in Fig. 3, 65 a central conductor being interposed between said sections and fastened to said strip D, as hereinafter described. The object of the division of the chain into two sections is the adjustment of my belt to local action, if desired, this adjustment being attained by the charging of one section only, thus confining the electric action to that part of the belt. In this way the strip D, through the electrode E, forms one end of a circuit, the other end 70 of which is found either at E' or E².

Each cell of my chain consists, essentially, of a back and front plate fastened together with interposed excitant-holders. My preferred construction is shown at G, where the 80 plates are shown riveted together with fiber or other non-conducting rivets, the plates being thus insulated one from the other and short circuit avoided. The top plate in this cell is extended in an apertured and slotted 85 tongue G², while the bottom plate is continued in the other direction and turned back on itself, as shown at G³. Between the back and front plate is interposed the excitant-holder G⁴, preferably in two layers, as shown, 90 and hollowed out, as at G⁵, for the reception of the reagent for replenishing the same. The excitant-holder consists of layers of textile material best calculated for absorption, which have been soaked in a saturated solution of muriate of ammonia or other suitable well-known reagent. After having been thus soaked the textile pads are dried and are then ready for use. A proper opening is made in the back plate of the cell opposite the hol- 95 100

low in the excitant, and this opening is closed by the pivoted valve G⁶. The object of this construction is to enable the wearer to insert a wafer of muriate of ammonia or other reagent, as desired. The back plate is perforated at intervals, as shown at G⁷, in order to expose a proper excitant-surface for the absorption of water in the preparation of the cells for action. This preparation consists in simply immersing the cell or cell-chain under water until the excitant has absorbed a sufficient quantity of fluid to set up brisk action in the circuit.

I find it best in manufacturing the chains, in order to preserve the front plate intact, to place next said front plate and against the front of the excitant-holder a plate G⁸, which acts with the rear plate of the cell in producing the current in the same. The cell G is shown provided with such a plate, having its outer edge turned up in order to facilitate its removal. The front plate in this construction simply acts as a conductor, and is not wasted by the mechanical action of the excitant.

The cell H in Fig. 1 is typical of the modified form of my cell, showing the plates held together by metallic rivets passing through apertures slightly larger than the rivets themselves, and insulated from the plates of the cell by means of non-conducting washers. These rivets are shown at H' and the washers at H². The front plate of the cell H is provided with a slotted ear H³, through the slot in which the ear G³ is passed. The back plate of the cell H is in all respects similar to that of the cell G, and is provided with a similar turned-back ear, save that there is no real aperture or valve for the same corresponding to G⁶. The excitant-holder within the cell H is not hollowed out, as may be seen in Fig. 2. This presents a slightly-cheaper form of cell not so easily replenished, but still useful in many connections. The middle conductor is shown at I, and consists of a plate having a hole I' near the middle of the same, and an offset recess I², communicating with said hole.

Apertured and slotted ears are provided at both ends of the cell-chain in every respect similar to that shown at G².

The method of fastening the end ears and central conductor is plainly shown in Fig. 1, and consists in simply slipping the same over the buttons F, F', and F² on the strips, and then drawing the shank of said button into the slots on said ears and conductor.

The method of fastening the metallic strips to the battery-section of the belts is shown in section at Fig. 2, where the strip D is shown fastened to the section B by means of the electrode buttons E, the end of the shank of each of which is turned over, as at E³, in order to secure the strip. The water-proof flap is shown in said figure at B², and the spring-button is shown secured beneath the water-proof facing of the section at F.

In using this belt the chain is detached from the belt immersed in water until the various cells have become properly moistened and then reattached in the position shown in Fig. 1. The water-proof flap is then buttoned down over the front of the chain, as above described, in order to save the clothes of the wearer. The belt is then applied to the body, the position of the chain varying with the case to be treated, but the flannel side of the belt being invariably placed next the body. The belt having been fastened in this position by means of the buckles C', it is evident that a double circuit will be set up, proceeding through each division of the belt, the middle strip, and each end strip. The therapeutic action of this current in cases of rheumatism, neuralgia, lumbago, and the like has been found extremely beneficial, and by properly varying the strength of the excitants and the metals used in the cells my belts may be adapted to wearers of different ages and sexes.

Where desired, only one-half of the circuit may be used by simply immersing one-half of the chain alone, a restricted and local action being the result.

I do not wish to be understood as limiting myself to the exact construction herein shown, nor to the precise number of cells employed, or arrangement in employment.

What I claim is—

1. A belt and metallic strips secured to one side of said belt by means of conducting attachments extending through the belt, in combination with a chain of cells constituting an electric battery, and means for attaching the ends of said chain to said strips, substantially as specified.

2. A belt and metallic strips secured to one side of said belt by means of conducting attachments extending through the belt, and a water-proof flap attached to said belt and adapted to fold over said strips, in combination with a chain of cells constituting an electric battery, and means for attaching the ends of said chain to said strips, substantially as specified.

3. A belt and metallic strips secured to the side of said belt by means of conducting attachments extending through the belt, in combination with a chain of cells constituting an electric battery, and spring-buttons secured to said strips and adapted to engage with said chain, substantially as specified.

4. A belt having three electrodes projecting through the same, in combination with a cell-chain having a central conductor, and means for connecting the ends of said chain and said conductor to said electrodes, substantially as specified.

5. A belt having three electrodes projecting through the same and a water-proof flap fastened to said belt and folding over said electrodes, in combination with a cell-chain having a central conductor, and means for

connecting the ends of said chain and said conductor to said electrodes, substantially as specified.

6. An electric cell for voltaic belts, consisting of a front and back plate and hollowed-out excitant-holder secured between the two, said back plate being perforated opposite said hollow, and a valve pivoted to said back

plate and swinging in front of said perforation, substantially as specified. ¹⁰

In testimony whereof I affix my signature in presence of two witnesses.

FRANK A. PHILLIPPI.
